CONDENSER SYSTEM

Louis A. Gebhard, Washington, D. C., assignor to
 Wired Radio, Inc., New York, N. Y., a corpora-
 tion of Delaware

Application December 22, 1928, Serial No. 327,990

14 Claims. (Cl. 175—41.5)

My invention relates to condenser systems in general and more specifically to certain structural and electrical features of electrical condensers employed in high frequency transmitters.

5 An object of my invention is to provide an improved condenser system for controlling the frequency characteristics and for neutralizing a thermionic tube transmitter.

Another object of my invention is to provide 10 an adjustable condenser unit for a high frequency transmitter wherein undesirable coupling of electrical energy is avoided.

Still another object of my invention is to provide 15 a condenser system which is compact and wherein equi-potential members of the frequency control and neutralizing units are placed together.

A further object of my invention is to provide 20 an arrangement of metallic plates constituting a compact and efficient adjustable capacity unit for controlling the frequency characteristics and balancing a thermionic tube high frequency transmitter.

Other and further objects of my invention 25 reside in the structural features and positioning of the several constituent units comprising the condenser system, a better understanding of which can be had by referring to the specification following and to the accompanying drawings 30 wherein:

Figure 1 is a schematic circuit diagram showing 35 the condenser system of my invention; Fig. 2 is a side elevation in part cross-section of the condenser system; Fig. 3 is a top plan view; Fig. 4 shows a transverse vertical view in section; Fig. 5 is a vertical longitudinal sectional view; Fig. 6 is a side elevation in cross-section showing one 40 of the adjusting features and Fig. 7 is a front elevation showing a section of the panel and one form of the indicating mechanism employed with the condenser system of my invention.

To obtain successful operation at high frequencies in high power transmitters it is necessary to arrange the parts in such a way that the leads 45 will be very short and undesirable couplings avoided. The parts must also be designed to withstand the rated voltage and current. These two requirements generally work against each other. If the parts are made large enough to withstand the required voltage the leads may be too long. One of the most serious problems lies in balancing the tuning condensers for the higher power stages.

Fig. 1 of the accompanying drawings shows 55 a schematic circuit diagram employing the con-

denser system of my invention. Thermionic tubes 1 and 2 are connected in an electrically balanced circuit arrangement. Thermionic tubes 1 and 2 have cathodes 3 and 4, control electrodes 5 and 6 and anodes 7 and 8 respectively. Cathode 3, control electrode 5 and anode 7 of thermionic tube 1, are supplied with energy from sources 9, 11 and 12 respectively. Control electrode 6, cathode 4 and anode 8 of thermionic tube 2 are supplied with energy from sources 11, 10 and 12 respectively. The input circuits of thermionic tubes 1 and 2 include inductance 13 and capacity 14. The output circuit of tube 1 includes the anode 7 thereof, a portion of inductance 18 between the center tap 21 thereof and the condenser 19, and the capacitive plates 26, 27 and 29, all of which are electrically connected with one another. The output circuit of tube 2 includes the anode 8 thereof, the portion of inductance 18 between the center tap 21 thereof and the connector 20, and the capacitive plates 24, 25 and 28, all of which are electrically connected with one another. The plates 26, 27, 29, 24, 25, and 28, are stationarily supported and are interleaved by the movable plates 22, 23, 30, 30a, 31a and 31. The 40 four plates last mentioned are electrically interconnected with one another and insulated from all of the other plates while plates 22 and 23 are respectively insulated from one another and from all the other plates. The electrical center 21 of inductance 18 is connected to source 12 and thence to the common cathode connection of thermionic tubes 1 and 2. Control electrode 5 of thermionic tube 1 is electrically connected to plate 22 and, by means of connector 15, to inductance 13. Control electrode 6 of thermionic tube 2 is electrically connected to plate 23 and, by means of connector 16, to inductance 13. The electrical center 17 of inductance 13 is connected to source 11 and thence to the common cathode connection of thermionic tubes 1 and 2.

In the operation of high frequency transmitters my condenser system may be used to neutralize or balance the thermionic tubes. This constitutes a method of balancing the system 100 wherein the anode of each of a pair of tubes is capacitively coupled to the input circuit of the other tube. The interaction between the tubes may be controlled and limited by varying the capacitive coupling so as to annul or neutralize 105 discrepancies or unlike characteristics of the tubes themselves.

Condenser plate 24 is at the same high frequency potential as anode 8. Condenser plate 22 is at the same high frequency potential as 110

control electrode 5. Similarly condenser plate 26 is at the same high frequency potential as anode 7 of thermionic tube 1 and condenser plate 23 is at the same high frequency potential as 5 control electrode 6 of thermionic tube 2. Since condenser plates 22 and 23 are adjustable in respect to plates 24 and 26 the energy transfer from the anode of one tube to the control electrode of the other is controlled by the capacitive 10 relation between the respective condenser plates. Providing thermionic tubes 1 and 2 have like inherent frequency characteristics, capacities formed by the relation of the above mentioned plates will approximately correspond. Unlike 15 frequency characteristics may be counter balanced by adjusting one set of movable plates in respect to the other. The state of balance requires a given value of energy to be transferred back to the control electrode of one tube from the 20 anode circuit of the other, which value is controlled by this adjustment.

In balanced thermionic tube circuit arrangements it is essential that the frequency characteristics of the inductance circuits of the balanced tubes be varied equally. It is for this reason that I prefer to include in the structural details of my condenser system a common driving mechanism for moving the plates 22 and 23. These plates, however, are insulated from one another. The plates 30, 30a, 31a and 31, may also be moved as a unit under a separate control. Thus the capacity relationships on the two sides of the inductance 18 may be varied in equal amounts. As will presently be shown, my invention provides a very compact arrangement of the condenser plates for controlling the frequency characteristics of the inductance 18 as well as for neutralizing the system wherein an electrical balance is to be maintained, and for 40 shielding the several units in respect to each other.

Referring now to Fig. 2, it will be seen that the condenser system in its entirety is built into a suitable frame-work 40, portions of which are of 45 insulating material. Condenser plates 25, 22 and 24 shown in Fig. 1 are concealed in Fig. 2 by the wall member 24a. Plates 26 and 27 are shown in section with a section similar to 24a removed.

Plates 26 and 27 are integral with thermionic 50 tube socket 1a. As is well known in the art, the metallic socket is at the same potential as the anode of the respective tube. Condenser plate 23, shown in Fig. 1 is here shown as comprising telescoping members 23a and 23b, the latter slidably positioned over the former. Plate member 23a is positioned vertically. Member 23b is fixedly mounted as to rotary movement but is movable vertically. The effective capacity area is adjusted by causing plate member 23b to move 60 vertically telescoping over member 23a or to move in the opposite direction thereby exposing a larger surface of member 23a. Members 23a and 23b, as also all of the plates, may be of aluminum, brass or other metal. The mechanism for causing the plate 23b to telescope over the plate 23a includes vertical shafts 43 and 43a, bevel gears 44, 44a and 47, the shafts 45, 45a and 45b, the gear train 49 and the handle 46 for manually adjusting the same. In order that the plate system 65 23a-23b may be kept insulated from the plate system 22, the two ends of the shaft 45 are insulated from one another as by the enlarged center portion thereof. The two ends of the shaft 53 are insulated from one another in like 70 manner. It will be understood, however, that in-

sulation may be provided at other points, if desired, for accomplishing the same purpose.

As will be more clearly seen upon reference to Fig. 5, the shafts 43a and 43 terminate at their lower extremities in threaded portions 68 and 80 68a respectively, these being screwed into the internally threaded tubular members 69 and 69a, respectively.

These tubular members are secured to the bottom portions of the plates 22 and 23, being prevented from turning by the pins 70. Suitable bearings 48 are provided (as shown in Fig. 2) for the shafts 43 and 43a whereby the bevel gears 44 may be enabled to mesh properly. Sufficient clearance is provided between the tubular members 69 and 69a (as shown in Fig. 6) and the inner walls of the plate 23b so that the latter may be telescoped over the plate 23a by rotation of the shafts 43 and 43a. A similar structure is, of course, provided for the two portions of the plates 22 although this is concealed from view in Fig. 2.

Fig. 3 shows in plan view the mechanically interconnected arrangement of the four vertical shafts such as 43, 43a and 43b whereby the load imposed upon the driving mechanism for lifting 100 the lower portions of the plate members 22 and 23b may be evenly distributed.

Figs. 2 and 4 show how the plates 30, 30a 31a and 31 are suitably spaced and interconnected by the bottom supporting member 37. Another 105 spacing member 37a is provided at the top for interconnecting the plates 30a and 31a. Member 37 is provided with two bushings 37b which are threaded preferably both internally and externally and which are firmly secured therein. The 110 internal threading of these bushings is adapted to accommodate the threaded portions of the shafts 38 and 38a by which the plates are adjustably supported. Clearance holes are also provided in the spacing member 37a through 115 which these shafts 38 and 38a project. The shafts just mentioned are carried on suitable pivot bearings 39 which are held in position on the frame 40.

A gear train 55 actuated by the crank handle 120 54 and connecting with the shafts 38 and 38a through the shafts 53 and the bevel gears 42 provides the means for raising and lowering the system of plates 30, 30a, 31a and 31 for varying the capacitative coupling with respect to the 125 other plate members with which they are interleaved.

Figs. 3 and 5 show how the tubes 1 and 2 are shielded by the plate members 27 and 25, respectively, and by portions of the plate members 26 130 and 24, respectively. The tube sockets 1a and 2a are provided, as is customary for high power tubes, with water circulating connectors 36a and 35a, respectively.

An inductance 60 may be mounted near thermionic tube sockets 1a and 2a and connected with contact members 61 and 62. Contact members 61 and 62, as shown, are immediately adjacent to the thermionic tube sockets which makes possible the interconnection with conducting 140 members of short length. It is likewise shown in this illustration how plates 25 and 27 may be extended around thermionic tube sockets 2a and 1a respectively thus providing an adequate shield. The sides of plates 24, 25 and plates 26, 27 are 145 closed as shown at K and K' respectively. This provides a shield for the telescoping plate members controlled by handle 46. For the purpose of limiting the downward movement of the plate members 23b I provide a rod member 70 having 150

a head 72 which forms an abutment with the extremity of plate members 23a as represented at 71. The head 72 in abutting with the inner extremity 71 of plate members 23a prevents the further downward movement of plate 23b.

Fig. 7 shows the indicating system associated with the gear train 49. Windows 49c and 55c are positioned in panel 50 through which calibration of dials 49a, 49b, 55a, and 55b is visible. 10 Dials 49b and 55b may indicate relatively coarse adjustments and dials 49a and 55a indicate more precisely the settings. Handle 54 controls the main capacity unit and handle 46 the neutralizing or balancing capacity. The two may be interconnected and operated by a common control member if so desired.

The condenser system of my invention may be especially designed to meet the particular application desired. The number of stationary and 20 movable plates is not limited. Many modifications of the circuit arrangement shown in Fig. 1 are possible. Any number of thermionic tubes may be employed. While the condenser system of my invention is especially adapted to high 25 frequency transmitters employing thermionic tubes having their anodes cooled by a circulatory liquid, other uses for the invention will readily suggest themselves to those skilled in the art.

The condenser system of my invention may be 30 used in many electrical systems and arrangements not referred to in the foregoing specification or illustrated in the accompanying drawings and it is to be understood that my invention is not limited to the particular embodiment herein described and shown in the accompanying drawings but only by the scope of the appended claims.

What I claim as new and desire to secure by Letters Patent of the United States is as follows:

1. A condenser system comprising in combination 10 a plurality of stationary plates, said stationary plates comprising two individual groups, the plates of each group being electrically connected in series, said groups being electrically insulated each from the other, a set of movable plates 45 electrically connected in parallel and capacitively related to said stationary plates, means for moving said movable plates linearly in the direction of their respective faces, and an independent system of plates movable in capacitive 50 relation to said two groups of stationary plates.

2. A condenser system comprising in combination 55 a plurality of stationary plates, said stationary plates comprising two individual groups, said groups being electrically insulated each from the other, a set of movable plates electrically connected together and capacitively related to said stationary plates, and an independent system of plates electrically insulated from said other plates and movable in capacitive relation to said two 60 groups of stationary plates.

3. A condenser system comprising in combination 65 a plurality of stationary plates, said stationary plates comprising two individual groups, said groups being electrically insulated each from the other, a set of movable plates electrically connected together and capacitively related to said stationary plates, and an independent system of plates electrically insulated from each other and from said other plates and movable in capacitive 70 relation to said two groups of stationary plates.

4. A condenser system comprising in combination 75 two groups of stationary plates, each including individual elements electrically connected in series, two units of movable plates electrically insulated from each other and in capacitive rela-

tion to said stationary plates, and a set of movable plates electrically insulated from said stationary plates and units of movable plates and in a capacitive relation common to said groups of stationary plates.

80

5. A condenser system comprising in combination groups of stationary plates, each including individual elements electrically connected in series, units of movable plates electrically insulated from each other and in capacitive relation to said stationary plates, a set of movable plates electrically insulated from said stationary plates and units of movable plates and in a capacitive relation common to said groups of stationary plates, and means for simultaneously operating 85 said units of movable plates.

85

6. A condenser comprising in combination individual groups of stationary plates, each including plates electrically connected in series, said groups being electrically insulated each from the other, a set of movable plates electrically connected together and in common capacitive relation to said groups of stationary plates, an independent system of movable plates electrically insulated each from the other and from 100 said other plates and in capacitive relation to said groups of stationary plates, and means for simultaneously controlling the movement of said movable plates constituting said independent system.

100

7. A condenser system comprising in combination two groups of stationary plates, each comprising a plurality of plates connected in series, said groups being insulated from each other, a set of movable plates common to both groups of stationary plates, and independent 105 movable plates insulated from each other and in capacitive relation with said groups of stationary plates.

105

8. In a condenser system, in combination, a plurality of parallel stationary plates comprising 110 a plurality of groups of plates insulated from each other, each group including a multiplicity of plates connected in series, a set of movable plates insulated from said stationary plates, an independent system of movable plates insulated from each other and in capacitive relation with said groups of stationary plates, and means for advancing said set of movable plates and said independent system of movable plates toward said parallel stationary plates from opposite directions.

110

9. In a balanced thermionic tube system the combination of two groups of stationary plates insulated from each other, a set of movable plates adapted to control the capacitive relation of said groups of stationary plates, a plurality of individual plates insulated from each other and comprising individual capacities in capacitive relation with said groups of stationary plates respectively, and means for simultaneously controlling the effective values of said individual capacities.

10. A condenser system comprising in combination groups of stationary plates insulated from each other, a set of movable plates adapted to control the capacitive relation of said groups of stationary plates, a plurality of individual movable plates insulated from each other and associated in capacitive relation with said groups of stationary plates respectively, and means for simultaneously varying the effective capacity area between said individually movable plates and said groups of stationary plates.

11. A condenser system comprising in combination a system of stationary plates arranged in parallel relation, said system of stationary plates

115

comprising a plurality of groups of plates electrically insulated each from the other, each of said groups including elements electrically connected in series, a set of movable plates adapted to control the capacitive relation of said groups of stationary plates, a plurality of individual movable plates insulated from each other and capacitively related with said groups of stationary plates respectively, and means for simultaneously varying the effective capacity area of said last mentioned movable plates with respect to said groups of stationary plates.

12. A condenser system having two individual groups of stationary plates electrically insulated each from the other, a set of movable plates adapted to be capacitively related to said groups of stationary plates, and individually movable plates electrically insulated from each other and from said other plates and comprising individual capacities with said groups of stationary plates respectively.

13. A condenser system for a balanced thermionic tube circuit comprising in combination

groups of stationary plates, movable plates in capacitive relation to said stationary plates, individual plates insulated from each other and adapted to be capacitively related to said groups of stationary plates respectively, and means for simultaneously varying the effective capacity area of said individual plates with respect to said stationary plates.

14. A condenser system comprising in combination two groups of stationary plates each electrically insulated from the other, each group including a multiplicity of plate elements, a set of movable plates adapted to be capacitively related to said stationary plates, individual plates insulated from each other and each adapted to be capacitively related with one of said groups of stationary plates respectively, and means for simultaneously controlling the capacity relations between said individual plates and said stationary plates independently of the adjustment of said set of movable plates with respect to said stationary plates.
